CLAIM

The ornamental design for an umbrella base as shown and described.

DESCRIPTION

FIG. 1 is a top, front, right perspective view of the umbrella base of the present invention;

FIG. 2 is a bottom, front, right perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines depict portions of the article that form no part of the claimed design.

1 Claim, 6 Drawing Sheets
